UNITED STATES PATENT OFFICE

ANGUS R. GROSS, OF BALTIMORE, MARYLAND

COOLER

Application filed August 7, 1928. Serial No. 297,997.

This invention relates to oil or other coolers for use in cooling lubricating oil or other liquids, and the principal object of the invention is to provide a cooler, of condenser type, so constructed and assembled that the different elements may be readily secured in place without the use of screws or bolts; the different elements being soldered together to form a unitary structure.

Another object of the invention is to provide a cooler of the above type, having a maximum cooling surface and capacity, the same having a core of honeycombed units for the passage of the cooling medium, the core being constructed of substantially tubular units arranged in parallel staggered relation, the units having slightly enlarged polygonal heads at each end, and the adjacent faces of the polygonal heads being soldered together to prevent passage of liquid between the adjacent faces of the heads, while permitting the water or other liquid to pass through the units; and the slightly separated tubular body portions of the assembled units forming a tortuous passage between the soldered heads for the fluid to be cooled.

A further object is to provide a cooler in which the honeycombed core is first assembled, then slipped into an outer casing and soldered securely to it in order to separate the passages for the fluid to be cooled from the passages for the cooling medium then end plates are placed over the ends of the outer casing and soldered to the outer casing, suitable inlet and outlet pockets at each end of the casing being provided for the cooling medium.

I will explain the invention with reference to the accompanying drawings which illustrate one practical embodiment thereof to enable others to adopt and use the same; and will summarize in the claims the novel features of construction, and novel combinations of parts, for which protection is desired.

In said drawings:—

Fig. 1 is a side elevation of the cooler.

Fig. 2 is a horizontal section on the axis of the cooler.

Fig. 3 is an enlarged vertical section through the unit heads.

Fig. 4 is an enlarged vertical section through the body of the core.

Fig. 5 is a perspective view of one of the core units.

Fig. 6 is an end view, partly broken away, of the cooler.

As shown, my novel cooler preferably comprises a honeycombed core within an outer casing 2, preferably polygonal in cross-section and open at its ends, casing 2 being provided with an inlet 2a and diametrically opposed outlet 2b adjacent its center. The ends of the casing 2 are enclosed by means of end plates 3 and 4 respectively provided with inlets and outlets 3a, 4a respectively, said plates having their edges flanged down around the sides of casing 2 and securely soldered thereto. End plates 3 and 4 are also provided with means for attaching the cooler to a support such as integral perforated lugs shown at 4b in Fig. 6.

The core is preferably built up of a plurality of sheet metal units 1a (Fig. 6) (preferably copper) of length somewhat less than that of casing 2, said units 1a being preferably substantially circular in cross section. The ends of each unit 1a are provided with enlarged polygonal heads 1b of substantial length, heads 1b being preferably expanded out of the sheet metal body of the units 1a.

A plurality of core units 1a are assembled in staggered relation, to form a polygonal core 1 to suit the polygonal cross-section of the outer casing 2, each face of each polygonal head 1b of the units contacting squarely with the opposed faces on the heads of the adjacent units, and these contacting faces of the hexagonal heads are securely soldered or otherwise united to form a unit, so that while water or other cooling medium may be passed freely through all the parallel core units 1a, such water or other liquid cannot pass between the soldered contacting faces 1b of the heads and into the spaces around the exterior of the core units, the soldered faces of the heads 1b forming substantial bulkheads transversely of the casing 2 except for the mouths of the units themselves. As previously stated, the heads 1b are somewhat enlarged over the diameter of the tubular

body portions of the cores $1a$, thus when the core is assembled a tortuous passage transversely of the core around the outer sides of the core units between the soldered heads $1b$ is provided, for a purpose hereinafter set forth.

In assembling the cooler, the honeycombed core is first built up of core units $1a$ having their enlarged heads $1b$ soldered together as above explained, the assembled core being of size to suit the size and shape of the outer casing 2 , which casing is preferably a little longer than the assembled core. The core is then placed within the casing 2 and the outer faces of the heads $1b$ at each end of the core are securely soldered to the inner walls of the casing 2 entirely around the casing so as to make a water-tight connection. The end plates 3 and 4 with their inlets and outlets $3a$ and $4a$ are then placed over the ends of casing 2 and also securely soldered thereto.

For the three above mentioned soldering steps, I use solders having successively lower melting points so that each successive soldering step will not destroy the one (or ones) previously applied.

By this construction the water may enter through the inlet $3a$ and spread out into pocket A between the plate 3 and the adjacent end of the core, and pass through the various core units $1a$ into the pocket B at the other end of the casing between plate 4 and the adjacent end of the core; from hence the water may pass through the outlet $4a$. The soldered contacting faces of the polygonal heads $1b$ of the core units and the soldered connections of the core to the inner walls of the casing form an effective bulkhead to prevent the entry of water between the heads $1b$ of the core and into the space around the exterior of the units $1a$.

The oil to be cooled may pass through inlet $2a$, around the exterior of the core units $1a$ between the soldered heads $1b$ and out through outlet $2b$. As shown in Fig. 4 a suitable baffle plate 5 may be interposed on the axis of the core, opposite inlet and outlet $2a$ and $2b$ and soldered in place to prevent the oil from passing directly from the inlet to the outlet, and assisting in spreading the oil so that the entire space between heads $1b$ around the units $1a$ will be filled with oil in order to obtain a maximum cooling effect. Baffle 5 however may be omitted.

By my novel construction a maximum cooling effect may be obtained as the core units are made of thin sheet metal which will readily conduct the heat of the oil to the water, also a maximum number of water passages through the core is obtained for a given diameter of casing 2 ; and the oil in passing through the cooler from inlet $2a$ to outlet $2b$ is caused to spread out into relatively thin sheets entirely enveloping the body portions of the core units $1a$, and the entire space with-

in the casing 2 not occupied by the water and tubes will be completely filled with oil.

Oil coolers, constructed in the above manner, are inexpensive to manufacture, making it possible to sell the coolers at a reasonable price. The soldered connections of the polygonal heads of the units makes a sufficiently strong water-tight joint, and no screws or bolts whatever are required in assembling the cooler. Where the casing 2 is of rectangular, octagonal, or other polygonal cross-section, the heads $1b$ of the core units should preferably also be of corresponding cross-section.

Obviously the cooler may be used for cooling other liquids and fluids than lubricating oil, and I do not so limit the use of the cooler. Nor do I limit my invention to the exact form shown in the drawings, for obviously changes may be made therein within the scope of the claims.

I claim:—

1. A cooler, comprising a casing polygonal in cross-section and having opposed inlet and outlet connections in the sides thereof; a preformed honeycombed core within the casing intermediate the ends thereof comprising a plurality of parallel tubular sheet metal core units having enlarged expanded heads at their ends corresponding in cross-section with that of the casing, the adjacent faces of the enlarged heads being fluid-tightly soldered together and to the casing; and end plates having inlet or outlet connections soldered to the ends of the casing.

2. A cooler, comprising a casing polygonal in cross-section and having diametrically opposed inlet and outlet connections in the sides thereof; a preformed honeycombed core within the casing intermediate the ends thereof comprising a plurality of parallel tubular sheet metal core units having enlarged expanded heads at their ends corresponding in cross-section with that of the casing, the adjacent faces of the enlarged heads being fluid-tightly soldered together and to the casing; end plates having inlet or outlet connections soldered to the ends of the casing, a baffle plate extending between and soldered to the core units opposite the inlet and outlet in the casing sides; and means on the end plates for attaching the cooler to a support.

3. A cooler, comprising a casing polygonal in cross section, a plurality of parallel tubes within the casing having enlarged polygonal heads on their ends, said heads being closely fitted together laterally and united by dipping in solder and the outermost heads being also closely fitted to the inner wall of the casing, the united heads forming partitions in the casing adjacent the ends thereof and united thereto by solder; and heads provided with flanges fitted over the ends of the casing and united thereto by solder and provided with openings for inlet and outlet of

fluid passing through the tubes; said casing having an inlet and outlet intermediate said partitions for the passage of fluid around and exterior of the tubes.

- 5 4. A cooler, comprising a casing body polygonal in cross section, a plurality of parallel tubular members within the body placed side by side, said members having enlarged heads at their ends adjacent the ends of the body
- 10 said heads being closely fitted together laterally, and the outermost heads being also closely fitted to the inner wall of the body so that the heads form partitions therein adjacent the ends thereof, said tube heads being
- 15 firmly united to each other and to the walls of the casing by dipping in solder; and heads having flanges fitted to the ends of the body and secured thereto by solder, said heads closing the ends of the body and respectively
- 20 provided with an inlet and an outlet for fluid to be passed through the tubes; said body having an inlet and an outlet intermediate the said partitions for the passage of fluid around and exterior to the tubes, all joints
- 25 being sealed by solder.
